UNITED STATES PATENT OFFICE.

FREDERICK E. TURNER, OF KANSAS CITY, MISSOURI, ASSIGNOR TO KANSAS CITY ELEVATOR MANUFACTURING COMPANY, OF KANSAS CITY, MISSOURI, A CORPORATION OF MISSOURI.

TENSION-EQUALIZING AND SHOCK-ABSORBING DEVICE.

1,380,125.

Specification of Letters Patent. Patented May 31, 1921.

Application filed October 11, 1920. Serial No. 416,217.

To all whom it may concern:

Be it known that I, FREDERICK E. TURNER, a citizen of the United States, residing at Kansas City, in the county of Jackson and 5 State of Missouri, have invented certain new and useful Improvements in Tension-Equalizing and Shock-Absorbing Devices; and I do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

This invention relates to elevators, the primary object being to provide a tension equalizer and shock absorbing device, particularly applicable for use in connection 20 with elevator, including a multiple suspension so that the shocks and lifting strains will be approximately equally distributed to all of the cables connected to the elevator as well as to equalize the strains through- 25 out the hitch.

It is particularly the object of the invention to eliminate shocks and strains to the cables caused by sudden starts and stops of the elevator and to prevent one or more 30 cables from becoming slack so as to throw the strain and load upon the remaining cables.

Also, it is important to equally distribute the shocks and strains throughout the elevator lifting mechanism and my invention 35 contemplates the provision of means whereby this may be accomplished, the construction being such that the friction between the car and its guide rails, caused by uneven 40 loading, will be reduced, this being possible because of the fact that the car is suspended from two or more points instead of the customary single-point suspension in the center of the car crosshead.

45 In the drawings,—

Figure 1 is a perspective view of an elevator car, showing the construction of the shock absorbing springs, the equalizing links to which the cables are fastened, the 50 equalizing levers connecting the links and the springs, and the multiple suspension.

Fig. 2 is a side elevational view of an elevator car, parts being broken away to show my invention.

Fig. 3 is a cross sectional view on the line 55 3—3 of Fig. 2.

Fig. 4 is a detail view of a lever, showing the links for connecting the spring rod and a link for engagement with the cross links whereby two alining links are connected together.

Fig. 5 is a perspective view of the shock absorbing spring rod-supporting links, and

Fig. 6 is a view partly in elevation and 65 partly in section of a shock absorbing spring showing the arrangement thereof.

1 and 2 are the vertical elevator guides which guide the elevator car consisting of the vertical channels 3 and 4. The draw head is shown as comprising the parallel 70 top channel beams 5 and 6 and the basket or cage portion 7, the floor of which is secured to the vertical members 3 and 4 in any approved manner. The particular construction of the cage and its guides form no part 75 of my present invention, the invention being confined to the device for connecting the elevator car to the hoisting cables, etc.

Near the respective ends of the channel beams 5 and 6 are spring seats 8 and 9, which are supported upon the upper, outwardly projecting flanges of the channels in any well known manner and serve as abutments or seats for the coil springs 10 and 11, which provide resilient connections between the elevator and certain lever and link mechanism to be referred to hereinafter.

By reference to Fig. 1 it will be observed that the lower flanges of the channels 5 and 6 are provided with bearings 12 and 13 in which are mounted transverse pivot shafts 14 and 15, passing through the ears or projections 16 and 17 of the bearing clamps 18 and 19 on the levers 20 and 21. The levers 20 as well as the levers 21 are 90 preferably arranged in pairs and are adapted to rock about their respective fulcrums 14 and 15, the pairs of levers being arranged in alinement as shown in Fig. 1 and on opposite sides of the longitudinal center of the 95 elevator cage.

Projecting from the respective levers 21 at their outer ends are upstanding links 22, connected at their upper ends by a cross bar 23, from which projects an upstanding rod 24 having its upper end threaded as at 25 and passing through a plate 26, the upper extremity of the threaded portion of the rod 105

being provided with a tension nut 27 which may be screwed upon the threaded end of the rod 24 to increase the tension of the spring.

5 The inner ends of the levers 21 are provided with upstanding equalizing links 28, two for each lever 21 and the links 28 correspond to links 29 for the levers 20, the alining links 28 and 29 being connected by a cross link 30 to which the cables 31 and 32 are secured. The lever 20 is likewise provided with upstanding links 33, corresponding to the links 22 for lever 21 and said links are associated with the spring 10 15 in substantially the same way as are the links or levers 21 with the spring 11. Therefore, it will be observed that if the car is about to start, an upward pull on the cables 31 and 32 will exert an upward pull on the inner ends of the levers 20 and 21, distributing the shock or strain to the springs 10 and 11, the arrangement of levers being such that the pull will be equalized throughout the lever mechanism and prevent shock or strain being communicated to any particular cable.

10 It will also be observed that when the car comes to a sudden stop, the sudden strain or shock will be communicated to the entire lever and link mechanism and be absorbed 20 thereby so as to prevent undue strain being communicated to the cables.

15 If a heavy car is used, the tension of the springs 10 and 11 may be increased by screwing down the nuts 27 and 27' for the springs 11 and 10 respectively. If, however, the car is relatively light or the load is relatively light the tension on the springs may be relieved by unscrewing the nuts a sufficient amount. Therefore, it will be apparent 25 that the tension may be varied to accommodate varying conditions.

40 I prefer to arrange the levers in sets or pairs, as shown, although this will not be necessary under all conditions. Where they are so arranged, however, a more efficient 45 equalization and distribution of the shocks or loads may be had.

45 It will be observed from the foregoing that a device constructed in accordance with 50 my invention is adapted to be applied to ordinary elevators so as to absorb the strains and shocks and prevent slack in the cables, thereby enabling the elevator to successfully perform service for a longer period than 55 would be possible where the strains were allowed to be localized in the hoisting mechanism.

What I claim and desire to secure by Letters-Patent is:

60 1. In combination, an elevator, a yieldingly supported device connected to the elevator, said device comprising a pivoted lever, a yielding connection between the elevator and one end of the lever, and a

cable connection at the other end of the 65 lever.

2. In an elevator tension equalizing, and shock absorbing device, sets of parallel levers, the sets being in alinement, means for yieldingly connecting the outer ends of 70 the sets of levers to the elevator, and means connecting the inner ends of the adjacent sets of levers together.

3. In an elevator tension equalizing and shock absorbing device, sets of parallel 75 levers, the sets being in alinement, means for yieldingly connecting the outer ends of the sets of levers to the elevator, means connecting the inner ends of the adjacent sets of levers together, and cables connected to 80 the last named means.

4. In an elevator tension equalizing and shock absorbing device, a pivoted lever on one side of the center of the elevator, an alining, pivoted lever on the opposite side 85 of the center of the elevator, means yieldingly connecting the outer ends of the levers to the elevator, and cable-supported means for shackling the inner ends of said levers together.

90 5. In combination, an elevator and its drawhead, a pivoted lever on the drawhead, a second alining, pivoted lever on the drawhead, means yieldingly connecting the outer ends of the levers to the drawhead, and 95 cable-supported means for shackling the inner ends of said levers together, said means comprising upstanding links and a cross link connecting them.

6. In combination with an elevator drawhead comprising two parallel beams, transverse shafts journaled to the beams, alining pairs of levers carried by the shafts, upstanding links carried by the outer ends of said levers, cross links connecting the upstanding links, threaded rods carried by the cross links, coil springs surrounding said rods, spring seats on the beams, adjusting nuts on the rods and bearing upon the springs, and cable-attaching links connecting the inner adjacent ends of the alining 105 pairs of levers.

7. In combination with an elevator drawhead, alining, pivoted levers carried by the drawhead, an adjustable spring connection 110 for the outer end of said levers and the elevator drawhead, and means connecting the inner ends of said alining levers.

8. In combination with an elevator drawhead, alining, pivoted levers carried by the 115 drawhead, an adjustable spring connection for the outer end of said levers and the elevator drawhead, and cable-securing links connecting the inner ends of said alining levers.

In testimony whereof I affix my signature.

FREDERICK E. TURNER.
